FOLDED PAPER NAPKIN

Original Filed May 6, 1925

Inventor:
Herbert L. Magill
by Clarence Loftus *att'y*

UNITED STATES PATENT OFFICE.

HERBERT L. MAGILL, OF CHICAGO, ILLINOIS.

FOLDED PAPER NAPKIN.

Original application filed May 6, 1925, Serial No. 28,360. Divided and this application filed November 14, 1925. Serial No. 68,958.

This application is filed as a division of my application Serial No. 28,360, filed May 6, 1925.

My present invention relates to improvements in sheets of folded material, and particularly to fold paper napkins.

The object of the present invention, as illustrated in the drawings and described in the specification, is to provide a sheet of folded material for use as a napkin with a plurality of non-coextensive sections so arranged as to afford a plurality of offset edges which may be easily grasped by the user and the napkin readily unfolded by removing it from a dispenser or superimposed pile by merely lifting the napkin after having grasped it by one of its offset edges.

Generally described, in carrying out the invention, a sheet of thin crepe paper material is folded along parallel lines in opposite directions in such a manner as to produce a number of centrally arranged coextensive panels or sections with end sections of less extent. The sections thus formed are then folded transversely intermediate their ends or off center so that the non-coextensive end sections are outermost, thus providing outermost edges which may be easily grasped and the article lifted or removed from a suitable receptacle or stack, during which active removal of the napkin is automatically unfolded and ready for use.

Figure 1 is a plan view of a sheet of paper showing the lines along which it is folded in carrying out the initial step of my invention;

Figure 2 is a perspective view showing the napkin in its completely folded or finished form; and

Figure 3 is a similar view illustrating a modification thereof, that is, when the folds first formed are afterwards folded off center.

Referring to the drawings in detail, a blank sheet of paper or other material to be used may be of any suitable size. The sheet shown in Figure 1 is first folded in opposite directions along substantially parallel lines, indicated by the reference character 10, whereby to make a fold of the accordion pleat type. With the sheet thus folded there is provided a plurality of substantially coextensive sections indicated by the reference

characters 12, and non-coextensive end sections 13. The sheet thus folded forms a long rectangular article which is then folded transversely intermediate its ends, substantially on the line 14, to provide the completed form of the article shown in Figure 2.

It will thus be seen that with my invention there is provided a number of centrally arranged coextensive sections 12, with end sections 13 considerably smaller than the centrally arranged sections so as to provide non-coextensive end sections to afford offset edges which may be easily grasped by the user in taking the article for use. By providing the non-coextensive end sections at both ends regardless of which direction the parts are folded transversely, there will always be provided outer sections which are non-coextensive with the centrally arranged ones.

In Figure 3 I have shown a modified form. The advantage of this form is that when the article is dispensed from a receptacle through a restricted window or opening such, for example, as a vertical receptacle having a restricted opening in one of its sides, the sheet is folded transversely off center, substantially on the line 15, so that one set of folded sections of the napkin is considerably shorter than the other set to provide offset edges 16 which, in practice, can be easily grasped by the user through the opening or window.

Having thus described my invention, I claim:

1. A tissue paper napkin folded into folds of the accordion-pleat type, and having an end section which is non-coextensive with the adjacent section, the sheet being then folded transversely to cause the non-coextensive end section to be in exposed position to be grasped by the user for unfolding the napkin.

2. A sheet of material folded into a plurality of substantially coextensive sections, and an end section which is non-coextensive with the other sections, the sheet being then folded transversely to cause the non-coextensive end section to lie along one edge at the top and bottom thereof.

3. A stack of sheets each comprising a sheet of material folded into folds of the accordion-pleat type and having a free and non-interlocking end section which is narrower than

the other sections, said sheets so folded being then folded transversely, thereby exposing an end section on both sides in a position to be grasped by the user.

5. A tissue paper napkin folded into folds of the accordion-pleat type, with an outer section non-coextensive with the adjacent in-

ner section, the sheet then being folded transversely with the non-coextensive outer section in exposed position whereby it may be ¹⁰ grasped by the user.

Signed at Chicago, Illinois, this 12th day of November, 1925.

HERBERT L. MAGILL.
